UNITED STATES PATENT OFFICE.

HENRY L. DOHERTY, OF NEW YORK, N. Y.

METHOD OF MOVING HOT FLUIDS.

1,187,052.

Specification of Letters Patent. Patented June 13, 1916.

Original applications filed November 15, 1911, Serial Nos. 660,449 and 660,450. Divided and this application filed July 16, 1912. Serial No. 709,797.

To all whom it may concern:

Be it known that I, HENRY L. DOHERTY, a citizen of the United States, and a resident of New York city, in the county of 5 New York and State of New York, have invented certain new and useful Improvements in Methods of Moving Hot Fluids, of which the following is a specification.

This invention relates to methods of moving hot fluids, and in particular to a method 10 of moving hot gases by ordinary blowers.

The object of my invention is to make practicable the moving of hot gases by means of ordinary blowers, when the temperature of the gases is high enough to cause injury to the blowers, without materially reducing the temperature of the gases at the place of use.

This application is a division of my applications Ser. Nos. 660,449 and 660,450, filed 20 Nov. 15, 1911, in which the subject matter of the present application is disclosed but not claimed.

Briefly stated, my invention comprises 25 the passage of the hot gases through a heat interchanger in which the current of gas is doubled back upon itself, the initial cooling of the said gases at a mid point in their path through the said heat interchanger, 30 and the continuous exertion upon the said gases at the locality in their path at which said initial cooling is established of the necessary propulsive effort to move the gas, whereby the hot gases may be moved by the 35 ordinary fan or positive blowers and delivered by the same without material reduction of their initial temperature.

By my invention, I am able to use hot producer or other gas, at substantially the 40 temperature at which it leaves the generator, in furnaces in which the pressure existing is above that in the generator, without imparting any additional heat to the gas. The heat of the gases discharging from the furnace is thus left available for utilization in other ways, such as the heating of the air used in sustaining combustion in the furnace in which the gas is burned, or in other furnaces. Even where the combustion gases 45 cannot be economically otherwise used than in preheating the air and gas supplied to the furnace, my invention permits of a much greater economy in operation in that the gas is delivered to the regenerators of the furnace already at a comparatively high tem-

perature. It is thus possible to preheat both the air and gas used in the furnace to nearly or quite the temperature of the furnace. This is never possible in the case of ordinary methods of firing with producer gas owing 60 to the fact that the combined thermal capacities per degree of the air and gas is considerably in excess of the thermal capacity of the products of the combustion per degree. There are also many other advantageous uses to which my invention may be put in metallurgical and industrial operations. 65

In the accompanying drawings, I have shown, more or less diagrammatically, an 70 apparatus embodiment of my invention adapted to advantageously carry out the process which is the subject of this application.

Figure 1 is a vertical section through the 75 apparatus on the line E, b, b', b'', b''', F of Fig. 4 looking to the left. Fig. 2 is a horizontal cross-section of the apparatus on the line C—D of Fig. 4. Fig. 3 is a vertical section on the line E, b, b', b'', b''', F, looking to the right. Fig. 4 is a vertical section 80 of the apparatus on the line A—B of Fig. 3 and A'—B' of Fig. 1. Fig. 5 is a partial fragmental vertical section, generally like that of Fig. 4 but on an enlarged scale and 85 showing a modification.

The form of apparatus shown in the drawings is one adapted to carry out my invention in connection with the method of heating a bank of vertical retorts which 90 is disclosed in my application Ser. No. 670,339 referred to above.

1 is the gas producer, having a fuel-preheating chamber 2, a gas-generating chamber 3 and a fuel-cooling chamber 4. 95

5 is the heat-interchanger, which comprises, a plurality of passages 6 for the gas going to the fan blower 7, and a plurality of passages 8 for the gas discharging from the fan. These passages are formed by dia- 100 phragms 9 built into a wide flue left in the front wall 10 of the gas producer 1. Nostrils 11 in the arch 12 establish communication between the passages 6 and the gas-collecting space 13 of the gas-generating chamber 3, which is formed under the arch 12 between the free face 14 of the fuel and the portion 15 of the front wall of the producer. 105 The passages 6 are in communication with the space 16 left in the heat-interchanger 110

above the upper ends of the diaphragms 9. Members 17, fitting substantially gas-tight between the diaphragms 9 and with the front portion and rear portion 18 of the 5 wall 10, prevent any leakage of gas directly from the space 16 to flues 8. A partition 19, separates the space 16 from the space 20 in the top of the heat-interchanger. An opening 21, having a diameter corresponding to 10 that of the suction inlet of the fan 7, is made in the partition 19.

In the arrangement of apparatus shown, the fan blower 7, which is of the "Sirroco" type, well known to the art, is directly 15 mounted on the shaft 22 of the motor 23. The casing of the motor is of a special design arranged so that it may be bolted directly to a heavy plate 24, which is in turn bolted or otherwise fastened to a frame in 20 the front wall 10 around the opening 38 in the front wall. The plate 24 is preferably made in two sections arranged to be bolted together over the shaft 22, an axial semi-circular bearing being borne by each section. 25 The plate 24 having been assembled and the casing of motor 23 bolted thereto, the plate is itself fastened in position. The shaft 22 should be of such length that the exterior face of the fan casing will make as close a 30 fit as is practicable with the partition 19. Upon operation of the fan 7, gas is drawn from the space 16 through the opening 21 and discharged into the space 20. A plurality of passages 25 in the upper part of 35 wall 10, establish communication between the space 20 and the flues 8.

A plurality of passages 26 in the lower portion of the part 18 of wall 10, establish communication between the flues 8 and the 40 cross-flue 27, which in turn is in communication with the gas flues 28, 28' which conduct the gas to the flue 29 from which it discharges into the lower combustion flue 30 of the furnace 31, through the nostrils 32.

45 The main draft current supplied to the producer enters the same through the passage 33, which is in communication with a draft-distributing space 34 formed under the arch 35 by the rear wall 36 and the free 50 surface 37 of the fuel. This draft current may be air, air and steam after the usual practice, air and gases of complete combustion, combustion gases alone, when the temperature of the same is sufficient to sustain 55 the reaction in the producer, or any practicable combination of gases that it may be considered desirable to use.

In the particular embodiment of my invention selected for illustration, the draft 60 current comprises a very hot balanced draft of completely burned and incompletely burned gases. The total volume of the draft current is so regulated with respect to the proportions of carbon dioxid and water 65 vapor, and the temperature of the gases,

that the amount of sensible heat carried by the draft current will be sufficient to support the dissociation of the desired proportion of the carbon dioxid and water-vapor. The hot draft current enters the fuel bed—the 70 main current passing through the fuel in gas-generating chamber 3 to the space 13, while a subdivision of the draft is drawn up through the fuel in the preheating chamber 2, heating and distilling the fuel and cooling the gas, and then forced into the cooler 75 4 by blower 39. This present invention, however, is not concerned with the composition of the draft current used and the specific method of generating gas, and a detailed description of the method of operating the producer is therefore unnecessary.

The active constituents of the draft-current, in passing through the ignited fuel in gas-generating chamber 3, react with the 85 fuel to produce carbon monoxid and hydrogen, principally in relative proportions depending upon the composition of the draft current, the temperature of the fuel, and various other conditions. Relatively small 90 quantities of methane, and various hydrocarbon gases derived from the volatile matter of the fuel are also present.

The main current of the combined gaseous stream, including such of the original constituents of the draft current as were unacted upon by the fuel, pass out of the free 95 surface 14 of the fuel into the gas-collecting space 13. From 13, under the induction exerted by the fan 7, the gases pass through 100 the nostrils 11 into the up-cast flues 6, through the space 16 to the opening 19 communicating with the suction inlet of the fan 7, thence through the fan to the space 20, through passages 25 to the downcast flues 8, 105 and down through flues 8 in contact with the diaphragms 9 separating the flues 8 from the flues 6.

At the start of operations, with the flues and setting cold, the gases ascending 110 through the flues 6 are subjected to a decided cooling action as they ascend. Since the gases are in contact with the heat-transmitting diaphragms 9, these latter, therefore, assume a temperature gradually increasing from approximately the temperature at which the gases reach the space 16, at the top, to approximately the temperature at which the gases enter the flues 6 at 115 the bottom. The gases leaving the fan and passing downward through the downcast flues 8 in contact with the other sides of diaphragms 9, are subject to reheating by heat transmitted through the diaphragms. Owing to the impossibility of transferring 120 heat from one current to the other without a greater or less temperature difference between the two currents, the initial loss of heat to the setting, etc., the temperature at 125 which the gases discharge from flues 8 is 130.

seldom or never as high as that at which the gases enter flues 6. With proper design of apparatus, however, this temperature difference may be maintained so small as to be practically negligible, from the point of view of heat economy.

It is plain that, as long as the quantity of gas passed through the heat-interchanger 5 is kept within the heat-transferring capacity of the heat-interchanger, a temperature differential having once been established between the gaseous current in space 16 and the gaseous current discharging from space 13, will thereafter be maintained indefinitely, so long as no extraneous heat is imparted to the current discharging from the fan. Whenever the fan is started up, however, after a temporary shut-down too short to permit of the cooling of the setting, or when the fan is run at a speed that moves the gas at a rate beyond the heat-transferring capacity of the apparatus 5, it may be that sufficient cooling action will not be exerted upon the gas passing to the fan through flues 6 and connecting passages to reduce its temperature to a point that will not injure the fan. When, due to any cause at all, such a condition arises, the necessary cooling of the gas must be accomplished by direct means. In the embodiment of my invention herein described, I meet this condition in one of two ways. First, I may open valve 40 on the connection 41 from the waste gas stacks 42-42' to the gas space 16. In this case, relatively cool waste combustion gases from the stacks 42-42', which have been cooled in the recuperators 43-43' by the air supplied for sustaining the combustion in the combustion flues of the furnace 31, are drawn down through the connection 41 into the space 16, to mingle with the gas entering 16 from flues 6, and thereby reduce the temperature of the mixture to a point that will not injure the fan 7. In this case, the initial direct cooling action of the cool combustion gases upon the draft going to the fan, is increased by the fact that the increased volume of gases passing through the down-cast flues 8 increases the heat-carrying capacity of this stream of gases over that of the gases ascending through the flues 6. This increases the rapidity of the abstraction of heat from the ascending gases, with the result that the temperature of the gaseous stream reaching the space 16 fall progressively if the conditions remain unchanged. Therefore, the proper heat differential having once been established, the valve 40 should be gradually closed until fairly constant temperature conditions have been established.

The introduction of the combustion gases into the producer gas has, of course, the effect of diluting the latter in proportion to the volume introduced. In other words, it

has the effect of diminishing the calorific value of the producer gas per unit of volume, but does not, of course, reduce the actual number of potential thermal units carried by the gas going to the furnace. In 70 many cases this result is advantageous, since it has the effect of reducing the flame temperature in the combustion flues of the furnace without reducing the actual heat generation therein. When a high temperature 75 is desired in the furnace, however, the quantity of combustion gases introduced should be reduced to the minimum quantity that will insure of the gases from the producer reaching the fan 7 at a sufficiently low temperature. This establishment of the necessary temperature in the gases at the fan, when the highest available temperature is desired in the furnace, is best effected by the second method. According to this, instead 80 of opening valve 40, valve 44 on the connection 45 from the discharge pipe or blower 39 to the connection 41 below valve 40, is opened. Instead of combustion gases, the cold and relatively rich gas that has been 85 drawn off from the upper part of the fuel preheating chamber 2, flows to the space 16 and mingles with the hotter producer gas. The degree of opening of valve 44 is of course regulated to permit only the volume 90 required to enter 16. The proper temperature difference having once been established, the flow of cool gas to 16 is gradually reduced, as in the first method of establishing the temperature differential, until constant 95 conditions have been established. By this second method, the producer gas is enriched instead of impoverished since the gas drawn off of the top of chamber 2 has been enriched by the addition of volatilized hydrocarbon 100 compounds of the coal.

When applied to the operation of gas producers and other gas generators of the ordinary types, without the return of any of the producer gas to the gas-generating chamber, 110 unless some other practicable cooling agent is available, the initial cooling may be effected by placing an ordinary coil of piping in the space 16 and circulating cold water therethrough. The area of the coil must, of course, be sufficient to effect the temperature reduction desired; or an exterior air-cooled conduit may be provided, through which the gas is passed before going to the fan. In this case, the upper terminations of the flues 6 are temporarily closed by dampers and the gas is drawn off to the external cooling passage, cooled and returned to the space 16. Since the extraneous cooling is only required during a brief period (as long as the capacity of the heat-interchanger is not exceeded) the loss in efficiency due to the heat abstracted from the gas by the coils or other apparatus is not appreciable. In Fig. 5 is shown more or less diagrammatically a 115 120 125 130

- vice wherein such initial cooling may be effected. In this structure the passages 6 may be temporarily closed off by damper 51 and the gases then pass through flue 46, port 47 and bypass port 48, valve 49 being open to the space above the damper where they may be cooled by water circulating in pipes 50, thereafter going to the fan in the manner hereinbefore described.
10. It is obvious that the temperature range through which the gas may be carried in the heat-interchanger depends, only, upon the nature and extent of the heat-transmitting surface of the latter.
15. Having described my invention, I claim:
1. The method of moving hot gaseous media by gas-moving apparatus, which comprises, establishing heat-transferring relationship between the gaseous current flowing to said apparatus, and the gaseous current discharged from said apparatus, withdrawing heat from the first portion of the said gaseous current immediately in advance of said apparatus by bringing said first portion into heat-transferring relationship with another fluid, and rejecting the heat so withdrawn.
  2. The method of moving hot fluids which comprises, exerting a propulsive effort upon a stream of fluid, at a mid point in a conduit, initially cooling said fluid by bringing the same into heat-transferring relationship with another body of fluid in advance of the locality at which the said propulsive effort is exerted, and establishing heat-transferring relationship between the portion of said stream flowing toward said locality and the portion of said stream flowing away from said locality.
  3. The method of moving hot fluids, which comprises, exerting a propulsive effort upon a stream of fluid by means of a suitable mechanism at a mid point in a conduit, initially withdrawing from said fluid at a locality in said conduit in advance of said mechanism sufficient heat to reduce the temperature of said fluid at such locality to a point that will not injure said mechanism by bringing said fluid into heat-transferring relationship with another body of fluid, and establishing heat-transferring relationship between the portion of said stream flowing away from said mechanism and the portion of said stream flowing to said mechanism, whereby the cooled portion of said stream flowing away from said mechanism is reheated by the portion of said stream flowing toward said mechanism, and the latter portion of said stream is cooled by the portion of said stream flowing away from said mechanism.
  4. The method of moving hot fluids, which comprises, exerting a propulsive effort upon a stream of fluid by means of a suitable mechanism at a mid-point in a conduit,
- initially withdrawing from said fluid at a locality in said conduit in advance of said mechanism sufficient heat to reduce the temperature of said fluid at such locality to a point that will not injure said mechanism by bringing said fluid into heat-transferring relationship with another fluid, and establishing counter-current flow in heat-transferring relationship between the portion of said stream flowing away from said mechanism and the portion of said stream flowing to said mechanism, whereby the relatively cool portion of said stream flowing away from said mechanism is reheated by the portion of said stream flowing toward said mechanism, and the latter portion of said stream is cooled by the portion of said stream flowing away from said mechanism.
5. The method of moving hot fluids, which comprises, exerting a propulsive effort upon a stream of fluid, by a suitable propelling means at a mid-point in a conduit, withdrawing from the portion of said stream of hot fluid flowing to said propelling means sufficient heat to reduce the temperature of said fluid to a point that will not injure said propelling means by bringing said stream of hot fluid into heat-transferring relationship with another fluid, rejecting the heat withdrawn from the first portion of said fluid approaching said propelling means, and thereafter transferring the heat withdrawn from the portion of the said stream flowing to said propelling means to the portion of said stream flowing away from said propelling means, whereby the latter portion of said stream is reheated.
6. The method of moving hot fluids, which comprises, exerting a propulsive effort upon a stream of fluid by the action of a suitable propelling means at a mid-point in a conduit, continuously withdrawing from the portion of said fluid stream flowing to said propelling means sufficient heat to reduce the temperature of said fluid to a point that will not injure said propelling means by bringing said stream of fluid into heat-transferring relationship with another fluid, rejecting the heat withdrawn from the first portion of said fluid approaching said propelling means, and thereafter continuously transferring the heat withdrawn from the portion of the said stream flowing to said propelling means to the portion of said stream flowing away from said propelling means, to reheat the latter portion of said stream to a temperature approximating its original temperature.
7. The method of moving hot fluids, which comprises, exerting a propulsive effort upon a stream of fluid by the action of a suitable propelling means, introducing into the stream of hot fluid flowing toward said propelling means a sufficient volume of relatively cool fluid to reduce the temperature

- of the resulting fluid mixture to a point that will not injure said propelling means, and establishing heat-transferring relationship between the stream of fluid flowing away 5 from said propelling means and the stream of fluid flowing toward said propelling means, whereby the former of said streams is reheated by the heat of the latter of said streams.
- 10 8. The method of moving hot fluids, which comprises, introducing into the stream of hot fluid flowing toward a propelling means a sufficient volume of relatively cool fluid to reduce the temperature of the resulting fluid mixture to a point that will not injure said propelling means, exerting a propulsive effort upon the cooled fluid mixture by the action of said propelling means, and establishing counter-current flow in heat-transferring relationship between the stream of fluid discharging from said propelling means and the stream of fluid flowing toward said propelling means, whereby the former of said streams is reheated as it flows 20 away from said propelling means and the latter of said streams is cooled as it approaches said propelling means.
9. The method of moving hot fluids, which comprises, introducing into the stream of hot fluid flowing toward a propelling means a sufficient volume of relatively cool fluid to reduce the temperature of the resulting fluid mixture to a point that will not injure said propelling means, exerting a propulsive effort upon the cooled fluid mixture by the action of said propelling means, establishing counter-current flow in heat-transferring relationship between the stream of liquid discharging from said propelling 30 means and the stream of liquid flowing toward said propelling means, whereby the former of said streams is reheated as it flows away from said propelling means and the latter of said streams is cooled as it approaches said propelling means, and regulating the volume of the cooled fluid introduced until the desired normal temperature condition has been established in said fluid stream at said propelling means.
- 40 10. The method of moving hot combustible gas from a gas generator to a combustion furnace without substantial reduction of temperature in the gas as delivered to said furnace, which comprises, conducting said combustible gas from said generator to said furnace through a suitable conduit, imparting a propulsive effort to said gas at a midpoint in said conduit by the action of a suitable propelling means, cooling a portion of said hot combustible gas, adding the said cooled portion of said combustible gas to the first portion of said hot combustible gas approaching said propelling means to reduce the temperature of the first portion of said 50 gas reaching said propelling means to a de-
- gree that will not injure the same, and then establishing counter-current flow in heat-transferring relationship between the stream of relatively cool gas discharging from said propelling means and the stream of initially 70 hot gas approaching said propelling means, whereby the former of said streams is reheated to approximately its original temperature while the latter of said streams is cooled to the temperature desired at said 75 propelling means.
11. The method of moving hot combustible gas from a gas generator to a combustion furnace without substantial reduction of temperature in the gas as delivered to said furnace, which comprises, conducting said combustible gas from said generator to said furnace through a suitable conduit, imparting a propulsive effort to said gas at a midpoint in said conduit by the action of a suitable propelling means, withdrawing sufficient heat from the gas approaching said propelling means to reduce the temperature of said gas to a point that will not injure said propelling means by bringing said gas 80 into heat-transferring relationship with a heat-absorbing fluid, rejecting the heat-absorbing fluid used to withdraw heat from the first portion of said combustible gas approaching said propelling means, and transferring the heat withdrawn from succeeding portions of said gas to the relatively cool gas discharging from said propelling means, whereby the said gas is reheated to approximately 85 its original temperature before it is introduced into said combustion chamber.
12. The method of moving hot combustible gas from a gas generator to a combustion furnace without substantial reduction of temperature in the gas as delivered to said furnace, which comprises, conducting said combustible gas from said generator to said furnace through a suitable conduit, imparting a propulsive effort to said gas at a midpoint in said conduit by the action of a suitable propelling means, cooling a portion of said hot combustible gas, adding the said cooled portion of said gas to the first portion of said hot combustible gas approaching said propelling means to cool the said 90 first portion of gas to a temperature that will not injure said propelling means, withdrawing heat from succeeding portions of said hot gas flowing from said generator, and transferring the heat withdrawn to the relatively cool gas flowing from said propelling means to said furnace by establishing counter-current flow in heat-transferring relationship between the two streams of gas, to cool the gas as it approaches said 95 propelling means and to reheat said gas to approximately its original temperature as it flows from said propelling means to said furnace.
13. The method of moving hot combus- 100

- tible gas from a gas generator to a combustion furnace without substantial reduction of temperature in the gas as delivered to said furnace, which comprises, conducting 5 said combustible gas from said generator to said furnace through a suitable conduit, imparting a propulsive effort to said gas at a mid-point in said conduit by the action of a suitable propelling means, introducing 10 into the initially hot combustible gas approaching said propelling means a sufficient volume of relatively cool gas to reduce the temperature of the resulting mixture to a point that will not injure the said propelling means, and establishing counter-current flow in heat-transferring relationship between the relatively cool gas flowing from said propelling means to said furnace and the hot generator gas flowing to 15 said propelling means, whereby the said gas is cooled as it approaches said propelling means and reheated to approximately its original temperature as it flows to said furnace.
- 20 25 14. The method of moving hot combustible gas from a gas generator to a combustion furnace without substantial reduction of temperature in the gas as delivered to said furnace, which comprises, conducting 30 said combustible gas from said generator to
- said furnace through a suitable conduit, imparting a propulsive effort to said gas at a mid-point in said conduit by the action of a suitable propelling means, introducing into the initially hot combustible gas approaching said propelling means a sufficient volume of relatively cool gas to reduce the temperature of the resulting mixture to a point that will not injure the said propelling means, establishing counter-current flow in heat-transferring relationship between the relatively cool gas flowing from said propelling means to said furnace and the hot generator gas flowing to said propelling means, whereby the said gas is cooled as it approaches said propelling means and reheated to approximately its original temperature as it flows to said furnace and regulating the volume of relatively cool gas introduced to establish and to maintain the normal desired temperature at the said propelling means. 35 40 45
